UNITED STATES PATENT OFFICE.

CHARLES E. CHAPMAN, OF FORT EDWARD, NEW YORK, ASSIGNOR OF ONE-HALF TO
JOSEPH GOODFELLOW, OF FORT EDWARD, NEW YORK.

WATER-TUBE BOILER.

Application filed July 2, 1921. Serial No. 482,019.

To all whom it may concern:

Be it known that I, CHARLES E. CHAPMAN, a citizen of the United States, residing at Fort Edward, in the county of Washington and State of New York, have invented certain new and useful Improvements in Water-Tube Boilers, of which the following is a specification.

This invention relates to improvements in water tube boilers.

The disadvantages attending the use of water tube boilers of the various types employing steam drums, boiler sheets, and other similar parts requiring rivets, are well recognized. Such boilers are incapable of withstanding high steam pressure particularly after they have been in use for any considerable period of time and are therefore liable to explode. Also such boilers are extremely difficult to clean if they become incrusted with scale, and they are equally difficult to repair if they become damaged, due chiefly to the fact that their parts cannot be conveniently disassembled, it being frequently necessary, in some types of such boilers, to dismantle practically the entire boiler in order to effect comparatively minor repairs. In consideration of the foregoing it is one of the objects of the present invention to provide a water tube boiler of such construction that the usual steam drums and boiler sheets are entirely eliminated and replaced by headers of a novel construction and capable of withstanding exceptionally high pressure.

Another object of the invention is to provide a novel means for connecting the water tubes of the boiler with the headers so that in the event any one of the water tubes becomes damaged or bursts, repairs may be effected without materially disturbing the connections of other tubes with the headers.

Another object of the invention is to provide a connection between the water tubes and headers of such construction as to withstand exceptionally high pressure, the invention contemplating also the provision, in connection with the means provided for uniting the water tubes to the headers, of clean-out plugs normally held in place with sufficient security to withstand the high pressure generated within the boiler and yet capable of being readily removed when it becomes necessary to remove scale from the

boiler, provision thus being made for cleaning of the boiler more conveniently and expeditiously than is possible in the usual constructions of boilers of this type.

Various other objects and advantages will be made apparent as the description of the invention proceeds.

In the accompanying drawings:

Figure 1 is a vertical transverse sectional view through a boiler constructed in accordance with the present invention;

Figure 2 is a sectional view taken substantially on the line 2-2 of Figure 1 looking in the direction indicated by the arrows;

Figure 3 is a detail vertical sectional view taken substantially on the line 3-3 of Figure 2;

Figure 4 is a top plan view of a portion of one of the headers.

Figure 5 is a detail sectional view illustrating one of the upper header connections;

Figure 6 is a similar view illustrating one of the lower header connections.

The boiler and its fire box are enclosed within side walls 1, a rear wall 2, and a front wall 3 which walls may be of any construction desired, and these walls surround and project above the plane of a top wall which is indicated in general by the numeral 4. Opposite each side wall 1, the furnace has built within its interior a baffle wall indicated in general by the numeral 5 and comprising a lower section 6 which is inclined upwardly and inwardly from a point adjacent the bottom of the respective side wall 1, and an upper section 7 which is

inclined upwardly and outwardly from the top of the section 6 to the plane of the top 4 and to a point adjacent the respective side wall 1. The lines of juncture of the sections 6 and 7 of the two baffle walls 5 are located horizontally opposite each other and in suitably spaced relation to accommodate the banks of water tubes at their crossing intermediate portions as will be evident by reference to Figure 1 of the drawings. The space between the baffle walls 5 and the respective side walls 1 constitutes a dead air space, and in order that the sections 7 of these walls may be afforded ample support, hollow bolsters 8 are arranged within the upper portions of the air spaces and each preferably comprises a bottom wall 9 secured at its outer edge to the respective

wall 1 and extending horizontally across the air space to the juncture of the sections 6 and 7 of the respective baffle wall; an upwardly and outwardly inclined wall 10 which extends upwardly from the inner edge of the wall 9 and affords a direct support for the bricks comprising the section 7 of the respective baffle wall; and, a top wall 11 which extends horizontally outwardly from the upper edge of the wall 10 and is secured to the respective wall 1. The wall 11 of each bolster constitutes a portion of the top wall 4 heretofore referred to as will be apparent by reference to Figure 1. A portion of the top wall 4 indicated by the numeral 12 is built up of fire brick and constitutes in effect an inward horizontal extension from the upper edges of the sections 7 of the baffle walls 5. The baffle walls 5, rear wall 2 and front wall 3 define the fire box of the boiler, and the products of combustion are conducted from the fire box through a stack 13 which opens at its lower end through the section 12 of the top wall 4. The numeral 14 indicates protective walls preferably of fire brick which extend horizontally inwardly from the lower edge of the section 6 of each baffle wall 5 and which, as also the sections 12 of the top 4, serve a purpose to be presently explained.

By reference to Figure 1 of the drawings it will be evident that as the front, rear and side walls of the boiler project above the top wall 4, an enclosed space is provided above this wall from which the flames are excluded, and similarly an enclosed space is provided beneath the protective walls 14 and the foundation upon which the boiler is constructed. The spaces above referred to are indicated respectively by the numerals 15 and 16 and constitute header spaces to house and protect from the flames the headers with which the water tubes of the boiler are connected, as will presently be pointed out. In order that access may be had to the spaces 15, each of these spaces is closed at its top by a door 17 preferably hinged at one side as at 18. Doors 17 are provided in the walls of the boiler at the bottom thereof so that access may be had to the lower header spaces 16.

The water tubes of the boiler are indicated by the numeral 19 and as will be evident by reference to Figures 1 and 2 of the drawings, these tubes are arranged in two banks disposed in the crossed relation illustrated in Figure 1 and inclined at angles corresponding to the angles of inclination of the sections 6 and 7 of the baffle walls 5. The water tubes of the two banks are arranged in staggered relation as shown in Figure 2 and each bank of tubes comprises a plurality of rows arranged in parallel relation, the tubes of the two banks crossing in the space between the juncture of the sec-

tions 6 and 7 of the two baffle walls 5. By reference to Figure 1 of the drawings it will be observed that the lower portions of the banks of tubes lie beneath the lower sections 6 of the respective baffle walls 5, and that the upper portions of the banks of tubes are inclined above the upper sections 7 of the baffle walls, the tubes of the two banks at their upper portions extending upwardly through the respective sections 12 of the top wall 4 and at their lower portions extending through the protective wall sections 14 as shown in the said Figure 1.

The upper ends of the water tubes of each row of each bank are placed in communication with a header located within the respective header space 15, and lower ends of the tubes of each row are placed in communication with a header in the respective header space 16, the upper headers being indicated in general by the numeral 20 and the lower headers by the numeral 21. Inasmuch as the headers are all of identical construction, a description of one will suffice for all. Each header is provided with a longitudinally extending passage way 22 and is formed at intervals in its side which is to be placed in communication with the associated water tubes, with tapered openings 23 communicating with the passage way 22. Each water tube at each end is provided with a circumscribing collar 24 preferably welded thereto, and beyond the collar the tube is exteriorly tapered as indicated by the numeral 25 adapting it to fit snugly in a wedging manner within the opening 23 in which it is to be received. At points suitably spaced from and at opposite sides of each opening 23, the header is provided with a plurality of openings 26 through which are passed bolt rods 27 each threaded at one end into the collar 24 of the respective water tube 19. Nuts 28 are threaded onto the other end portions of the bolt rods 27 and when these nuts are tightened to bind against the side of the header remote from the side into which the end 25 of the tube is fitted, the said end of the tube will be drawn tightly into the respective opening 23 and wedged therein in such a manner as to not only provide a steam-tight union but also to withstand a maximum degree of pressure.

Each header 20 is formed opposite each of the openings 23 with a tapered opening 29 communicating with the passage way 22, and a tapered plug 30 is fitted into this opening 29 as best shown in Figure 3 of the drawings and is provided at its outer end with a head 31 through which the outer ends of the bolt rods 27 project, nuts 32 being threaded upon the said ends of the rods and being adapted to be tightened so as to force the plug 30 into the opening 29.

and thus normally plug or seal this opening in a steam-tight manner. It will be evident that in order to clean any of the water tubes it is only necessary to remove the 5 plugs 30 located opposite the ends thereof which may be done by removing the nuts 32 and without in any way disturbing the connection of the water tube with the headers. Also it will be evident that access 10 may be had to the headers for the purpose of adjusting the connections of the water tubes and plugs 30 therewith by opening the doors 17 and through the opening closed by the doors 17'.

15 Regarding the construction illustrated particularly in Figure 3 of the drawings whereby the water tubes and plugs are connected and held to the headers, the fact will be appreciated that the push joint connection which is employed for this purpose constitutes a highly efficient means for uniting the tube ends to the headers and for holding the plugs 30 in place, the union effected being of such a nature as to withstand 20 enormous pressure and being entirely free from any possibility of leakage.

The numeral 33 indicates the fire box door at the front of the furnace and by reference to Figure 1 it will be observed 25 that the headers 21 at the lower ends of the water tubes of the two banks are located at opposite sides of the grate of the fire box, the headers of each bank being placed in communication with one another at their 30 front and rear ends through the medium of trunks 34 each provided at intervals in its lengths with tapered nipples 35 seated in the tapered ends 36 of the passage ways 22 of the headers as best shown in Figure 6, 35 bolts 37 being passed through flanges 38 and 39 which respectively surround the ends of the headers 21 and the nipples 35 and being adapted to be tightened so as to draw the nipples with a wedging engagement into 40 the said tapered ends of the passage ways 22 of the headers. By similar push joint connection indicated by the numeral 40, a plug 41 is fitted into and closes the outer end of one of the trunks 34 at the front and 45 rear of the boiler, and a water supply pipe 42 is connected by a similar push joint connection 43 with the outer end of the other trunk 34, the relatively adjacent ends of the trunks being placed in communication 50 with each other through the medium of a pipe 44 interposed between the same and connected thereto by push joint connections 45. This pipe 44 will extend between the fire box and ash pit doors of the boiler as 55 shown in Figure 1 of the drawings, both at the front and rear of the boiler in the event the boiler is to be fired from both the front and rear. Of course if the boiler is to be fired only from the front, a single 60 continuous trunk will be substituted for

the two trunks 34 illustrated in the said figure.

The ends of the passage ways 22 of the upper headers 20 are tapered as at 46 in the same manner as the ends 36 of the said passage ways in the case of the lower headers 21, and elbows 47 are provided with tapered reduced ends 48 and 49, the former being fitted into the tapered ends 46 of the passage ways 22 and being drawn tightly into 75 place by a push joint connection 50 similar to that previously described.

The tapered ends 49 of the elbows 47 are received in tapered openings 51 formed at suitable intervals in the upper sides of 80 trunks 52 and are drawn into place by push joint connections 53. The trunks 52 extend across the front and rear of the boiler and each is in communication with the adjacent ends of all of the headers 20 at the respective side of the boiler. One end of each trunk 52 is closed by a plug 54 wedged in place by a push joint connection 55, and by a similar connection 56 steam outlet pipes 57 are placed in communication with the 90 opposite ends of the two trunks and serve to conduct steam from the boiler.

The numeral 58 indicates a pipe which is tapped at its lower end into one of the trunks 34 at the front of the boiler and at 95 its upper end into the trunk 52 at the front of the boiler, and interposed in this pipe is a water gage 59 and a steam pressure gage 60.

In the operation of the boiler water is admitted through the supply pipe 42 and circulating through the lower trunks 34 and headers 21, rises in the water tubes 19 approximately to the level indicated in Figure 1 of the drawings and which may be 100 determined by inspection of the water gage 59. The flames from the fuel in the fire box will impinge directly against the lower portions of the water tubes, being directed by the lower sections of the baffle walls 5, and 105 the heated products of combustion will also impinge against the upper portions of the water tubes above the water level before passing out through the stack 13. Therefore by this arrangement each of the water tubes constitutes in effect an individual 110 boiler, and the upper portion of the tube above the water level constitutes a space in which the generated steam is heated to a higher temperature before being discharged 115 into the upper headers 20. However the baffle or protective walls 12 and 14 serve to prevent direct contact of the flames and heated products of combustion with the bolt rods 27 and associated parts so that there is no likelihood of deterioration of the connections establishing communication between the water tubes and headers. It will be evident that due to the inclination of the 120 water tubes, they are more effectually sub- 125

jected to the heat from the fire box than would be the case if they were vertically disposed.

It will be evident that by reason of the 5 tapered joint between the water tubes and headers, a much larger contact area is provided at the point of union than in the ordinary construction. It will also be evident that after the water tube ends have been 10 fitted into the openings in the headers, the steam pressure within the tubes will tend to bring about a still more intimate contact between the tapered ends of the tubes and the walls of the tapered openings in 15 which they are received thus automatically sealing the connections.

Having thus described the invention what is claimed as new is:

20 In a water tube boiler, a fire box, the said fire box comprising a back, a front, side walls, and a top, the top having a sunken portion at its intermediate part, a flue leading upwardly from the sunken portion and communicating with the fire box, upper partition walls extending between the side walls of the fire box and the sunken portion of the top and providing air spaces at the opposite sides of the flue, baffle walls extending between the front and back of the 25 fire box and inclined downwardly toward

each other, other baffle walls inclined downwardly and outwardly away from each other from the lower edges of the first mentioned baffle walls and extending likewise between the front and back of the fire box, 35 lower partition walls extending above the bottom of the fire box and between the lower portions of the last mentioned baffle walls and providing beneath them an air space, banks of water tubes arranged in 40 crossed relation with their lower portions extending parallel to the under sides of the respective second mentioned baffle walls and having their upper portions extending parallel to the upper faces of the respective 45 first mentioned baffle walls, the upper ends of the tubes of each bank extending through the upper partition wall and the lower ends extending through the lower partition wall, headers connecting the upper ends of the 50 series of tubes comprising each bank and located within the first mentioned air spaces, headers connecting the lower ends of the series of tubes comprising each bank and located within the last mentioned air 55 spaces, and means for supplying water to the last mentioned headers.

In testimony whereof I affix my signature.

CHARLES E. CHAPMAN. [L. s.]
